(57) **CLAIM**

The ornamental design for an electric vehicle, as shown and described.

DESCRIPTION

FIG. 1 is a front and right side perspective view of an electric vehicle showing our new design;

FIG. 2 is a rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is an exploded top, front and right side perspective view thereof;

FIG. 9 is an exploded rear and right side perspective view thereof; and,

FIG. 10 is an exploded right side elevational view thereof. The portions of the electric vehicle shown in broken lines represent unclaimed subject matter that form no part of the claimed design.
